(57) **CLAIM**

The ornamental design for a chair, as shown and described.

DESCRIPTION

FIG. 1 is a perspective view of a chair in accordance with the present invention;

FIG. 2 is a front view of the chair of FIG. 1;

FIG. 3 is a rear view of the chair of FIGS. 1-2;

FIG. 4 is a side view of the chair of FIGS. 1-3, the opposite side being a mirror image thereof;

FIG. 5 is a top view of the chair of FIGS. 1-4; and,

FIG. 6 is a bottom view of the chair of FIGS. 1-5.

The broken lines shown in the Figures are for environmental purposes only and form no part of the claimed design.

The dotted lines, shown on the seat, backrest and armrests in the drawing, are understood to represent stitching.
